UNITED STATES PATENT OFFICE.

HAMILTON T. HOWELL, OF WOODSIDE, NEW YORK.

DESIGN FOR AN ARTIFICIAL-LIGHT FIXTURE.

49,309.

Specification for Design.

Patented July 4, 1916.

Application filed May 22, 1916. Serial No. 99,245. Term of patent 3½ years.

To all whom it may concern:

Be it known that I, HAMILTON T. HOWELL, a citizen of the United States, residing at 4 Third street, Woodside, in the county of Queens and State of New York, have invented a new, original, and ornamental Design for Artificial-Light Fixtures, of which the following is a specification, reference being had to the accompanying drawing, in which—

Figure 1 is an elevation and Fig. 2 is a plan view, showing my new design.

I claim:

The ornamental design for an artificial light fixture, as shown.

HAMILTON T. HOWELL.

Witnesses:

CHARLES V. DWYER,
FREDERICK G. KIMLIN.
